STRIPING DEVICE

Antonio Fera, Vancouver, British Columbia, Canada, assignor of one-half to John George Musgrave, Vancouver, British Columbia, Canada

Application October 10, 1941, Serial No. 414,540
In Canada July 3, 1941

6 Claims. (Cl. 91—62.5)

This invention relates to an improved striping device.

An object of the present invention is the provision of a striping device capable of making a fine line.

Another object is the provision of a striping device capable of making anything from a fine to a relatively heavy or wide line.

Another object is the provision of a striping device which may be used in small grooves or the like.

A further object is the provision of a striping device which may be handled with ease by the operator.

A further object is the provision of a striping device which will not tire the operator's hand as rapidly as the devices in common use.

A still further object is the provision of a device of the nature described of simple and yet durable construction which cannot go out of working order.

Yet another object is the provision of a striping device which will not clog during use.

A still further object is the provision of a striping device which will always make a clean-cut line.

With these and other objects in view, the present invention consists essentially of a striping device comprising a cylindrical casing, a tapered nozzle at the lower end of the casing, a small tubular tip at the apex of the nozzle, a small passage through the apex and tip of the nozzle, a rod extending through the casing and beyond its upper end, said rod being tapered at its lower end to seat in the passage, an abutment on the rod beyond the casing, a trigger pivotally supported above the casing and extending towards the lower end thereof, an arm extending downwardly from the trigger adjacent its pivot to engage the abutment, means normally urging the rod downwardly to seat in the passage, and means through which liquid may be supplied to the casing, as more fully described in the following specification and illustrated in the accompanying drawing, in which

Figure 1 is a side elevation, partly in section, of the striping device,

Figure 2 is a plan view thereof,

Figure 3 is a section through the device taken adjacent its lower end,

Figure 4 is a perspective view of a yoke which is used on the device,

Figure 5 is an enlarged sectional view of an alternative nozzle arrangement, and

Figure 6 is an enlarged sectional view of the nozzle arrangement illustrated in Figure 1.

Referring more particularly to the drawing, 10 is a cylindrical casing having a tapered nozzle 11 at its lower end. This nozzle is preferably removably mounted on the lower end of the casing, as shown, and it has a tubular tip 12 extending outwardly from the apex thereof, while a small passage 13 extends through said apex and the tubular tip.

A rod 14 extending through the casing 10 and beyond its upper end 15, has a tapered lower end 16 which normally seats in the passage 13. The rod extends through a packing gland 17 carried by the end 15 of the casing.

A frame 18 is mounted on the upper end of the casing 10 and projects outwardly therefrom. This frame consists of spaced upper and lower arms 20 and 21, respectively, which merge together at their outer ends into an internally threaded collar 22. A boss 23 is formed on the upper arm 20 substantially midway between the ends thereof and a slot 24 extends longitudinally of said arm and through the boss.

A trigger 25 is pivotally mounted at 26 in the boss 23 and said trigger has an arm 27 extending downwardly therefrom adjacent its pivot through the slot 24. This arm straddles the rod 14 and engages an abutment 28 fixedly mounted on the rod within the frame 18. A tube 30, threaded into the outer end of the collar 22, has a knurled enlargement 31 at its outer end, and a spring 32 is positioned in said tube. This spring extends around the rod 14 and engages the end of the abutment 28 to urge the rod downwardly with its tapered end 16 seated in the passage 13.

The trigger 25 consists of a flat band of material extending downwardly from its pivot in a vertical plane 33, said material being twisted at 34 into a horizontal plane adjacent its outer end to form a finger rest 35. The trigger has a loop 36 at its pivot by means of which the device may be hung up.

A tube 37 communicates with the casing 10 adjacent its upper end and extends outwardly and rearwardly therefrom at an angle thereto. A cap 38 is removably mounted on the outer end of the tube 37 in any suitable manner, the cap in the drawing, being screwed thereon.

A yoke 40 is mounted on the casing in any desired manner. The yoke is preferably removably mounted on the casing and in the illustrated alternative, each arm 41 of said yoke is provided with an upwardly projecting lug 42 having an

opening 43 therein, through which a transverse rod 44 extends. This rod is removably retained in a boss 45 mounted on the casing 10 adjacent its lower end, by means of a set-screw 46. This rod may have a guide arm 37 at one end thereof projecting forwardly parallel to the nozzle 11 and, if desired, said rod may be provided with graduation marks 48 thereon.

The yoke 40 has a transverse section 50 extending across the tip of the nozzle and connecting the outer ends of the arms 41. A hollow tapered tip 51 is mounted on the section 50 of the yoke. This tip may be permanently mounted on or formed with the transverse section or it may be removably mounted thereon, as shown. The tip may be of any desired width and it has a slot 52 formed in its apex communicating with the interior thereof. The top 51 is retained in registry with the passage 13 of the nozzle 11 with the tubular tip 12 projecting into the tapered tip.

In use, the casing 10 is filled with the required liquid, such as paint, ink or lacquer, through the tube 37. In fact, for long periods of use with the same liquid at one place, a hose leading from a suitable reservoir may be attached to the end of the tube. As the liquid flows from this device by gravity, the device must be held either in a horizontal position, or with its nozzle end below the horizontal.

If a very fine line or stripe is required, or if the line is to be drawn in a small groove or the like, the yoke 40 and its associated elements may be discarded. In any case, the striping device is held very much the same as a pen or pencil with the index finger resting on the trigger 25. The shape of this trigger provides a very comfortable rest for the finger. The operator may press the side of his finger against the vertical plane 33 to steady said finger and the tip thereof naturally rests on the flat finger rest 35.

When it is desired to permit the flow of liquid, the trigger is pressed downwardly, causing the arm 27 to urge the abutment 28 upwardly against the pressure of the spring 32. This draws the rod 14 upwardly and raises its tapered end 16 from its seat in the passage 13 to allow the liquid to flow through the latter. The spring 32 normally urges the tapered end 16 into its seat and the pressure of said spring may be regulated by turning the tube 30 in the required direction. The small passage 13 of the tubular tip 12 permits only a comparatively small quantity of the liquid to flow at a time so that a thin line is formed, and said tip may be inserted into grooves or other small places where it is now very difficult to draw a line or a desired design.

If a wider line is required, the yoke 40 may be mounted on the rod 44 with its tapered tip 51 in registry with the passage 13. The width of the slot 52 determines the width of the line. If the tip 51 is permanently mounted on the yoke, several yokes may be provided having tips with slots 52 of different widths or, if the tip is removably mounted on the yoke, several of these tips may be provided having slots 52 of different widths.

The arm 41 may be used as a guide when the lines are drawn and the graduations 48 may be used to gauge the distance the line is to be drawn from the surface against which the guide arm bears.

An alternative nozzle arrangement is shown

in Figure 5. In this case, the yoke 49 is dispensed with and a hollow tapered tip 53, preferably formed of rubber, is provided. This tip may be fitted over the tubular tip 12 and it has an opening 54 in a wall thereof adjacent its apex. Several of these tips 53 may be provided having openings 54 of various sizes.

With this construction, the fluid flows out through the opening 54 and the width of this opening determines the width of the line being drawn.

From the above, it will readily be seen that a simple and durable striping device has been provided, which may be easily and comfortably manipulated by the operator, and with which anything from fine to relatively wide lines may be drawn.

Various modifications may be made in this invention without departing from the spirit thereof or the scope of the claims and, therefore, the exact forms shown are to be taken as illustrative only and not in a limiting sense, and it is desired that only such limitations shall be placed thereon as are disclosed in the prior art or are set forth in the accompanying claims.

What I claim as my invention is:

1. A striping device comprising a cylindrical casing, a tapered nozzle at the lower end of the casing, a small passage through the apex of the nozzle, a yoke mounted on the casing and extending across the nozzle tip, a hollow tapered tip mounted on the yoke, a slot formed on the apex of the tip, said tip being retained in registry with the nozzle passage, a rod extending through the casing and beyond its upper end, said rod being tapered at its lower end to seat in the passage, a trigger pivotally supported above the casing and extending towards the lower end thereof, means connecting the trigger to the rod, and means normally urging the rod downwardly to seat in the passage, and means through which liquid may be supplied to the casing.

2. A striping device comprising a cylindrical casing, a tapered nozzle at the lower end of the casing, a tubular tip at the apex of the nozzle, a small passage through the apex and tip of the nozzle, a yoke mounted on the casing and extending across the nozzle tip, a hollow tapered tip removably mounted on the yoke, a slot formed in the apex of the tapered tip, said tapered tip fitting over the tubular tip and being in registry with the nozzle passage, a rod extending through the casing and beyond its upper end, said rod being tapered at its lower end to seat in the passage, an abutment on the rod beyond the casing, a trigger pivotally supported above the casing and extending towards the lower end thereof, an arm extending downwardly from the trigger adjacent its pivot to engage the abutment, means normally urging the rod downwardly to seat in the passage, and means through which liquid may be supplied to the casing.

3. A striping device comprising a cylindrical casing, a tapered nozzle at the lower end of the casing, a tubular tip at the apex of the nozzle, a small passage through the apex and tip of the nozzle, a yoke removably mounted on the casing and extending across the nozzle tip, a hollow tapered tip mounted on the yoke, a slot formed in the apex of the tapered tip, said tapered tip fitting over the tubular tip and being in registry with the nozzle passage, a rod extending through the casing and beyond its upper

end, said rod being tapered at its lower end to seat in the passage, a trigger pivotally supported above the casing and extending towards the lower end thereof, means connecting the trigger to the rod, means normally urging the rod downwardly to seat in the passage, and means through which liquid may be supplied to the casing.

4. A striping device comprising a cylindrical casing, a tapered nozzle at the lower end of the casing, a tubular tip at the apex of the nozzle, a small passage through the apex and tip of the nozzle, a yoke removably mounted on the casing and extending across the nozzle tip, a hollow tapered tip removably mounted on the yoke, a slot formed in the apex of the tapered tip, said tapered tip fitting over the tubular tip and being in registry with the nozzle passage, a rod extending through the casing and beyond its upper end, said rod being tapered at its lower end to seat in the passage, an abutment on the rod beyond the casing, a frame projecting rearwardly from the casing around the rod, a trigger pivotally mounted on said frame and extending towards the lower end of the casing, an arm extending downwardly from the trigger adjacent its pivot to engage the abutment, a spring mounted in the outer end of the frame and pressing against the abutment normally to urge the rod downwardly to seat in the passage, means for adjusting the pressure of the spring against the abutment, and means through which liquid may be supplied to the casing.

5. A striping device comprising a cylindrical casing, a tapered nozzle at the lower end of the casing, a tubular tip at the apex of the nozzle, a small passage through the apex at the tip of the nozzle, a yoke mounted on the casing and extending across the nozzle tip, a hollow tapered tip mounted on the yoke, a slot formed in the apex of the tapered tip, said tapered tip fitting

over the tubular tip and being in registry with the nozzle passage, a rod extending through the casing and beyond its upper end, said rod being tapered at its lower end to seat in the passage, an abutment on the rod beyond the casing, a frame projecting rearwardly from the casing around the rod, a trigger pivotally mounted on said frame and extending towards the lower end of the casing, said trigger consisting of a flat band of material extending downwardly from its pivot in a vertical plane and twisted into a horizontal plane adjacent its outer end to form a finger rest, an arm extending downwardly from the trigger adjacent its pivot to engage the abutment, a tube threaded into the outer end of the frame, a spring positioned in the tube and pressing against the abutment normally to urge the rod downwardly to seat in the passage, the pressure on said spring being regulatable by turning the tube, and means through which liquid may be supplied to the casing.

6. A striping device comprising a cylindrical casing, a tapered nozzle at the lower end of the casing, a tubular tip at the apex of the nozzle, a small passage through the apex at the tip of the nozzle, a rod extending through the casing and beyond its upper end, said rod being tapered at its lower end to seat in the passage, an abutment on the rod beyond the casing, a trigger pivotally supported above the casing and extending towards the lower end thereof, said trigger consisting of a flat band of material extending downwardly from its pivot in a vertical plane and twisted into a horizontal plane adjacent its outer end to form a finger rest, an arm extending downwardly from the trigger adjacent its pivot to engage the abutment, means normally urging the rod downwardly to seat in the passage, and means through which liquid may be supplied to the casing.

ANTONIO FERA.
